UNITED STATES PATENT OFFICE.

CHARLES E. KEEL, OF INDIANAPOLIS, INDIANA.

STENOGRAPHIC TYPE-WRITING MACHINE.

No. 810,209

Specification of Letters Patent.

Patented Jan. 16, 1906.

Application filed July 22, 1904. Serial No. 217,655.

To all whom it may concern:

Be it known that I, CHARLES E. KEEL, a citizen of the United States, residing at Indianapolis, in the county of Marion and State of Indiana, have invented new and useful Improvements in Stenographic Type-Writing Machines; and I do declare the following to be a full, clear, and exact description of the invention, reference being had to the accompanying drawings, and to the letters and figures of reference marked thereon, which form a part of this specification.

This invention relates to machines that are designed for stenographic printing or mechanical shorthand-writing adapted to be operated by hand by stenographers while taking dictation or when reporting court proceedings, speeches, and other like matters delivered orally.

The prime object of the invention is to provide improved simple and inexpensive machines of the above-mentioned character constructed so as to be durable and economical in use and whereby the shorthand characters may be printed in comparatively small areas or spaces, so that conveniently small sheets or strips of paper may accommodate a great number of words or sentences.

A further object is to provide comparatively small and light-weight shorthand-machines in order that they may be readily carried about by stenographers from place to place as circumstances may require.

With the above-mentioned and other objects in view the invention consists in an improved rotative cylindrical platen, in improved type-bars and arrangement thereof, and in improved operating apparatus for the platen; and the invention consists, further, in the novel parts and the combinations and arrangements of parts, as hereinafter particularly described and claimed.

Referring to the drawings, Figure 1 is a top plan view of the complete machine as preferably constructed; Fig. 2 an end elevation, Fig. 3 a front elevation, Fig. 4 an end elevation, and Fig. 5 is a rear elevation, of the machine. Fig. 6 is a vertical sectional view centrally and longitudinally of the platen of the machine; Fig. 7, a fragmentary transverse sectional view, as at the line 1 1 in Fig. 6; Fig. 8, a fragmentary horizontal sectional view at a plane below the platen; Fig. 9, a fragmentary vertical sectional view at a plane near the front of the platen; Fig. 10, a longitudinal sectional view of the platen at

the line 2 2 in Fig. 7; Fig. 11, a fragmentary detail view showing parts of the spacing devices; Fig. 12, a top plan view of the type-bars; Fig. 13, a side elevation of a combined type-bar and key-lever, and Fig. 14 illustrates a fragment of paper having a sample of the shorthand-writing thereon.

Similar reference characters designate corresponding parts or elements in the several figures of the drawings.

In construction a suitable base *a* is provided, which serves to support the operative mechanism of the machine and maintain some of the parts in proper relative arrangement. Near one corner of the base a suitable pillar *A* is erected on the base and secured thereto, and an axle *B* is suitably secured to the pillar, so as to extend therefrom horizontally across a portion of the base. Preferably an end of the axle is screwed into a suitable hole in the pillar *A*, so as to be adjustable endwise, the axle extending through the pillar and having a lock-nut *b* thereon engaging the farther side of the pillar. The opposite free end of the axle has a screw *c*, binding a collar *d* against the end of the axle. A friction-collar *e* extends about the axle *B* against the pillar *A*, and a sleeve *C* is rotatively mounted on the axle, extending from the collar *e* to the collar *d*. A ratchet-wheel *f* is secured to the end of the sleeve adjacent to the collar *e*, and a toothed gear-wheel *g* is also secured to the sleeve adjacent to the ratchet-wheel, the latter providing a friction-surface against which the collar *e*, of suitable material, may act as a brake. The sleeve *C* is provided with a projecting feather *h* at the outer side thereof.

The platen *D* is cylindrical, having end heads *i* and *j* and a hub *k*, and is otherwise open or hollow, the hub being mounted movably on the sleeve *C* and having a longitudinal slot *l* receiving the feather *h*, so that the platen may move endwise on the sleeve, but cannot rotate thereon. A collar *m*, composed of suitable material to act as a cushion, is placed on the sleeve *C* against the wheel *g*, so that it may be engaged by the hub *k* of the platen when returning on the sleeve to its normal position. A rock-bar *E* has journals *n* and *n'* mounted in the heads *i* and *j* and is provided with arms *p* and *p'*, extending through suitable openings in the shell of the platen, there being integral clips *q* and *q'* at the ends of the arms adapted to bear against the outer surface of the platen and

to hold sheet paper on the platen, a spring r strained between the hub k , and the bar E normally holding the clips against the platen. A lever F has an arm s , that is pivoted to a stud t of the bar E , and a link u pivotally connects the lever to the hub k , the lever serving to raise the clips to insert or remove the paper. The platen is provided at its end that is nearest to the pillar A with an external screw-thread or worm G , extending spirally about the platen to serve as a means for moving the latter endwise on the sleeve C .

At the front of the platen D a suitable arm H is supported on the base a , so as to move radially, preferably by means of spring-hinges v and v' , the arm supporting a rack-bar w having notches x in the face thereof that is disposed toward the platen to receive the worm G , whereby to cause the platen to move endwise while rotating, the spring-hinges normally maintaining the connection between the rack-bar and the worm. A lever I is attached to the arm H and co-operates with a spring-arm J , secured to the base a , the arm having a stop-shoulder y to prevent the rack-bar from pressing against the worm and causing friction. The spring-arm also has a latch-shoulder z , that may be engaged by the lever I to hold the rack-bar w off and out of engagement with the worm. The arm H is shown as being nearly solid or webbed, with an opening 3 therein to afford space for other parts, and obviously other openings may be provided.

At the rear of the platen D is a curved spring-arm K , and in the same plane beyond the end of the platen is another spring-arm K' , adapted to press against the platen for holding paper thereto, the arms being secured to the base a , each arm having outwardly-turned lips 4 and 5 , that may be engaged by the ends of the platen when moving endwise past the arms, so that the latter may be prevented from obstructing the movements of the platen.

In a plane somewhat forwardly of the platen D a pair of ears 6 and 7 are secured to the base a , and a stiff rocking bar L has arms 8 and 9 , that are pivoted to the ears. The bar L is also provided with an arm 10 to serve in rotating the platen. A spring 11 , mounted on the base, presses the bar L upwardly and the arm 10 in direction from the platen. A lever M is mounted on the base a , preferably by means of a spring-hinge 12 , and extends across the top of the bar L to serve as a spacing-lever. A stand O is secured to the base a and is provided with a guide-bearing 13 , in which is slidably supported a rod N , that is pivoted at one end to the arm 10 , the opposite end of the rod being provided with a spring-catch P in engagement with the ratchet-wheel f for rotating the platen. Another stand O' is also secured to the base a , and a rotative shaft Q is journaled in the stands O and O' for operating an inking-rib-

bon, the shaft having a worm 14 secured thereto. Ribbon-spools R and R' are suitably mounted on the base a below the plane of the under side of the platen, the spool R being provided with a gear-wheel 15 in engagement with the worm 14 , an inking-ribbon 16 being wound on the pair of spools and extending under a portion of the platen D . A guide 17 is secured to the base a under the platen and supports guide-rolls 18 19 20 21 , guiding the ribbon close to the platen.

In a plane at the front of the platen between it and the bar L a stand for supporting the type-bars is mounted on the base a , the stand preferably comprising a base 22 , to which are adjustably secured a pair of ears S and S' , supporting a pivot-rod 23 , that extends between the two ears. Twelve type-bars, arranged as two sets of six bars each, as T T' T^2 T^3 T^4 T^5 and U U' U^2 U^3 U^4 U^5 , each have a bearing 24 , whereby they are mounted pivotally on the pivot-rod 23 . The type-bars extend through the guide 17 , in which the bars may rest, or may also move upwardly toward the platen, and on the top of each bar is a raised type V of suitable design, adapted to print, by means of the ink-ribbon, on paper that may be held on the platen. One set of the type-bars is intended to be operated by the right hand and the other set by the left hand of the operator, so that both complete sets may be operated simultaneously, if necessary, thumbs each operating two bars. It is designed that the characters on the right-hand set shall be used to form or indicate the initial sounds of words, syllables, or phrases and the other set the terminal sounds thereof. Various forms of characters of course may be employed consistent with shorthand systems, dots and dashes being used in the present invention. The type-bars extend forwardly beyond the bar L and have contact on the top thereof, being spread apart at their forward ends, forming integral key-levers, on each of which is a key W or finger-piece, having a character thereon corresponding to the printing character on the type-bar. The key-levers are each arranged between two posts 25 and 26 , forming guides, and rests on a spring 27 .

The machine is provided with a spool X at the rear of the platen, suitably supported on the base a , and a ribbon of paper may be drawn from the spool onto the platen in lieu of a sheet of paper to print upon. A presser-roll Y is suitably mounted at the front of the platen to hold the paper thereto, and a suitable stop 28 is provided to prevent end movement of the platen when printing on a continuous strip or ribbon of paper, the stop being suitably mounted movably on a pillar 29 , whereby also the roll Y is supported, the pillar also supporting a knife Z for severing pieces of the paper ribbon after having been printed upon.

The characters 30 in Fig. 14 represent the nature of the shorthand-writing that may be produced on the machine.

In practical use when it is desired to use 5 sheets of paper on the machine the left-hand edge of the paper will be held by the clips *q q'* and wrapped about the platen *D*, the latter being placed in the position shown in the drawings with respect to its support or 10 against the collar *m*. The stop 28 must be withdrawn from the end of the platen, and the worm *G* being in engagement with the rack-bar *w* the writing or printing may be accomplished by operating the keys so as to 15 press them down and also force the type characters upwardly against the ink-ribbon, the latter against the paper. When one or more of the key-levers descends, the movement will depress the bar *L* and cause the 20 catch *P* to advance idly and drop into a notch in the ratchet-wheel *f*. With the return upward movement of the key or keys, caused by the springs 11 and 27, the catch *P* will rotate the wheel *f*, and consequently the 25 sleeve *C* and also the platen, a distance sufficient for a space between two words, and at the same time the worm *G* and rack-bar *w* will cause the platen to advance slightly endwise on the sleeve *C* toward its outer end. 30 The position of the right-hand side of the paper with respect to the types may be indicated by observing the lever *F* or by other suitable indicator, and when a line has been written or printed the spacing-lever *M* may 35 be used to rotate the platen a short distance, so that another line may be begun on the left-hand side of the sheet of paper, and then the operation of the keys may be continued until the sheet is full, line after line, when 40 the platen will have moved endwise on the sleeve *C* partly beyond the end thereof. Then the rack-bar *w* is to be withdrawn by means of the lever *I*, so that the platen may be returned endwise to its former position to 45 receive a new sheet of paper for further use. In this arrangement the lines will be slightly inclined to the horizontal on the paper. When it is desired to print a single line on a continuous ribbon of paper, the lever *I* will be 50 held by the shoulder *z* of the arm *J* so that the worm *G* cannot coöperate with the rack-bar *w* and the stop 28 will be placed against the end of the platen, the latter thus being 55 prevented from moving endwise, while it may be rotated by the usual operation of the keys and also by means of the spacing-lever *M*. The results of the operations of other parts will be understood from the description of their construction.

60 The various elements comprised in the machine may be somewhat modified when manufacturing in large quantities, and in extra large machines with long platens the axle *B* obviously may be provided with a support at

its free end. Additional type-bars may be 65 added, if desired.

Having thus fully described the invention, what I claim as new is—

1. A stenographic type-writing machine including a base, a pillar supported on the base, an axle secured to the pillar, a platen supported by means of the axle so as to move rotatively and also longitudinally, a plurality of type-bars coöperating with the platen, paper-holding clips carried by the platen, a rack-bar mounted on the base and spring-pressed toward the platen, a device attached to the platen for coöperation with the rack-bar, a latch mounted on the base, a lever connected with the rack-bar for the control thereof and 75 in coöperation with the latch, and mechanism coöperating with the platen for the rotation thereof and adapted to be operated by the simultaneous operations of all of the plurality of type-bars. 80

2. A stenographic type-writing machine including a base, a pillar supported on the base, an axle secured to the pillar, a platen mounted on the axle so as to rotate and also move longitudinally, means for rotating the platen, 90 a plurality of type-bars coöperating with the platen, a rack-bar mounted on the base, an actuating device carried by the platen for coöperation with the rack-bar, a spool mounted on the base to hold a paper ribbon, a presser-roll supported by the base and coöperating with the platen to hold the ribbon thereto, means for holding the rack-bar out of contact with the actuating device, and a stop mounted on the base adapted to prevent the longitudinal movement of the platen. 100

3. A stenographic type-writing machine including a base, a pillar supported on the base, an axle secured to the pillar, a platen mounted on the axle so as to rotate and also move 105 longitudinally, means for rotating the platen, a plurality of type-bars coöperating with the platen, a rack-bar mounted on the base, an actuating device carried by the platen for coöperation with the rack-bar, a spool mounted on the base for holding a paper ribbon, a presser-roll supported by the base and coöperating with the platen to hold the ribbon thereto, means for holding the rack-bar out 110 of contact with the actuating device, a stop mounted on the base adapted to prevent the longitudinal movement of the platen, and a knife supported in proximity to the presser-roll. 125

4. A stenographic type-writing machine including a base, a pillar supported on the base, an axle secured to the pillar, a sleeve mounted rotatively on the axle and provided with a ratchet-wheel, a platen mounted on the sleeve so as to move longitudinally thereon and also 120 to rotate therewith, a plurality of type-bars coöperating with the platen, a rack-bar supported by the base and spring-pressed toward

the platen, an actuating device carried by the platen for coöperation with the rack-bar, a latch supported by the base, a lever connected with the rack-bar and coöperating with the latch, and means coöperating with the ratchet-wheel and the type-bars adapted to rotate the sleeve and the platen.

5. A stenographic type-writing machine including a base, a pillar supported on the base, an axle secured to the pillar, a sleeve mounted rotatively on the axle and provided with a ratchet-wheel and also a gear-wheel, a platen mounted on the sleeve so as to move longitudinally thereon and also to rotate therewith, a plurality of type-bars coöperating with the platen, means coöperating with the ratchet-wheel and the type-bars adapted to rotate the platen and the sleeve, a pair of spools mounted on the base, an ink-ribbon wound 15 on the spools, a rotative shaft mounted on the base and having a pinion engaging the gear-wheel, operating means connecting the shaft with one of the spools, a rack-bar supported by the base, and a device attached to 20 the platen for coöperation with the rack-bar serving to move the platen longitudinally on the sleeve.

6. A stenographic type-writing machine including a base, a pillar supported on the base, an axle secured to the pillar, a sleeve mounted rotatively on the axle and provided with a gear-wheel, a platen mounted on the sleeve so as to move longitudinally thereon and also to rotate therewith, a plurality of type-bars 35 coöperating with the platen, a rocking bar provided with a spacing-lever and adapted to be operated by the type-bars, means coöperating with the rocking bar and the platen to rotate the platen, a spring-pressed arm mounted 40 on the base provided with a controlling-lever and supporting a rack-bar, a latch mounted on the base and engaging the controlling-lever, an actuating device carried by the platen and coöperating with the rack-bar, a pair of spools mounted on the base, an ink-ribbon wound on the spools, and means coöperating with the gear-wheel and the spools to operate the ribbon.

7. A stenographic type-writing machine including a base, a pillar supported on the base, an axle secured to the pillar, a sleeve mounted rotatively on the axle and provided with a ratchet-wheel, a platen mounted on the sleeve so as to move longitudinally thereon and also to rotate therewith, a plurality of type-bars 55 coöperating with the platen, a rack-bar mounted movably on the base, a latch mounted on the base, a controlling-lever connected with the rack-bar and coöperating with the latch, an actuating device carried by the platen adapted to coöperate with the rack-bar, a rocking bar extending in proximity to parts of the type-bars so as to be operated thereby and provided with a movable arm, a 60 rod connected to the movable arm of the

rocking bar and provided with a catch coöperating with the ratchet-wheel, and a spacing-lever coöperating with the rocking bar.

8. A stenographic type-writing machine including a base, a pillar supported on the base, an axle secured to the pillar, a sleeve mounted rotatively on the axle, a platen mounted on the sleeve, a stand mounted on the base, a pivot supported by the stand, a plurality of type-bars mounted on the pivot and provided collectively with two identical sets of printing characters, one set of the characters being adapted to form or indicate the initial sounds of words, syllables or phrases and the other set the terminal sounds thereof, the characters consisting of dots and dashes, and mechanism coöperating with the sleeve and also with the type-bars to rotate the platen.

9. In a stenographic type-writing machine, the combination with a fixedly-supported pillar, of an axle having one end thereof adjustably attached to the pillar and provided with a collar at the opposite end thereof, a sleeve mounted rotatively on the axle between the pillar and the collar, and provided with a feather at the outer side thereof, a platen having a hub provided with a slot receiving the feather of the sleeve, a cushion-collar on the sleeve with which the inner end of the platen-hub may have contact, a plurality of type-bars coöperating with the platen, a ratchet-wheel secured to the sleeve, mechanism coöperating with the ratchet-wheel for rotating the sleeve and the platen, a movable rack-bar, an actuating device carried by the platen coöperating with the rack-bar for moving the platen longitudinally on the sleeve, and a controlling-lever for the rack-bar connected therewith.

10. In a stenographic type-writing machine, the combination with a plurality of movable type-bars having operating-levers, of a fixedly-supported axle, a sleeve mounted rotatively on the axle and provided with a ratchet-wheel, a platen mounted on the sleeve so as to move longitudinally thereon and also to rotate therewith in proximity to the type-bars, a rocking bar extending in proximity to the operating-levers of the type-bars so as to be operated thereby and provided with an arm, a rod pivoted to the arm of the rocking bar and having a catch coöperating with the ratchet-wheel, and means for operating the rocking bar independently of the operating-levers of the type-bars.

11. In a stenographic type-writing machine, the combination of a base, a pillar mounted on the base, an axle secured to the pillar, a platen supported by means of the axle so as to move rotatively and also longitudinally, a plurality of type-bars coöperating with the platen, means for moving the platen rotatively and also longitudinally, a rocking bar journaled in the platen and having arms provided with clips coöperating with the platen, a spring 130

coöperating to draw the clips against the platen, and a lever mounted on the platen and connected with the rocking bar for the operation of the clips.

5 12. In a stenographic type-writing machine, the combination of a base, a pillar mounted on the base, an axle secured to the pillar, a platen supported by means of the axle so as to move rotatively and also longitudinally, 10 a plurality of type-bars coöperating with the platen, means for moving the platen rota-

tively and also longitudinally, paper-holding clips carried by the platen, and a spring-arm mounted on the base coöperating with the platen and provided with outwardly-extending lips for guiding the arm. 15

In testimony whereof I affix my signature in presence of two witnesses.

CHARLES E. KEEL.
